Des. 236,339
Patented Aug. 19, 1975

236,339

CIRCULAR TRAILER WINDOW

Lynn S. Polk, San Bernardino, Calif., assignor to
Le Van Specialty Company, Inc.

Filed June 18, 1973, Ser. No. 371,248

Term of patent 14 years

Int. Cl. D12—16

U.S. Cl. D12—183

FIG. 1.

FIG. 2.

FIG. 3.

FIG. 4.

FIG. 5.

FIG. 1 is a front elevational view of a circular trailer window, showing my new design;

FIG. 2 is a rear elevational view thereof;

FIG. 3 is a side elevational view thereof;

FIG. 4 is a transverse sectional view thereof taken substantially on line 4—4 of FIG. 2; and

FIG. 5 is a vertical sectional view thereof taken substantially on line 5—5 of FIG. 1.

I claim:

The ornamental design for a circular trailer window, as shown.
